CLAIM

The ornamental design for the bicycle roller trainer flywheel, as shown and described above.

DESCRIPTION

FIG. 1 is a front, right perspective view of a bicycle roller trainer flywheel showing our new design;

FIG. 2 is a left side view thereof;

FIG. 3 is a right side view thereof;

FIG. 4 is a front side view thereof;

FIG. 5 is a rear side view thereof;

FIG. 6 is a top view thereof; and,

FIG. 7 is a bottom view thereof.

The broken lines in the figures show portions of the bicycle roller trainer flywheel that form no part of the claimed design.
